UNITED STATES PATENT OFFICE.

JOSEPH H. KOEBEL, OF WAYLAND, IOWA.

END-GATE FOR WAGONS.

1,098,450.

Specification of Letters Patent.

Patented June 2, 1914.

Application filed August 5, 1912. Serial No. 713,233.

To all whom it may concern:

Be it known that I, JOSEPH H. KOEBEL, a citizen of the United States, residing in the city of Wayland, county of Henry, and 5 State of Iowa, have invented certain new and useful Improvements in End-Gates for Wagons, of which the following is a specification.

This invention relates to improvements in 10 end gates for wagons and has among its salient objects to provide a construction which is self locked against endwise or lateral displacement, and at the same time so interlocks with the side boards as to prevent 15 spreading of the latter; to provide a construction of the character referred to which dispenses with any tie rods, locking bolts or other extraneous fastening devices; to provide a construction in which the end 20 gate is equipped with a plurality of anti-friction rollers whereby the former may be readily slipped into or out of engagement with the side boards; to provide a construction in which the end gates form a tight 25 fit with the side boards so as to prevent leakage of grain or other similar material, in which the end gates and side boards effectively brace each other so as to form a rigid 30 structure and in which the end gate may nevertheless be removed or inserted in place 35 without binding; to provide a construction in which the end gates may be made, if desired in a plurality of sections, and to provide simple and novel means for locking the sections 40 together and for locking the end gates as a whole against vertical displacement; to provide a construction in which the interlocking parts are in effect concealed, thus 45 not only preventing injury to such parts, but giving a workman-like appearance to the end gates as a whole; and in general to provide simple and economical construction 50 of the character referred to.

The invention consists in the matters hereinafter described and more particularly pointed out in the appended claims.

In the drawings Figure 1 is a rear end elevation of a wagon equipped with my improved end gate; Fig. 2 is a fragmentary 55 top plan view of the construction shown in Fig. 1; Fig. 3 is a fragmentary horizontal sectional view taken on lines 3-3 of Fig. 1 and looking in the direction of the arrows; Fig. 4 is a similar view taken on lines 4-4 60 of Fig. 1 and looking in the direction of the arrows; Fig. 5 is a fragmentary vertical sec-

tional view taken through the central part of the gate.

Referring to the drawings 1 designates the bottom or bed of a wagon body, 2 and 3 the side boards and 4 the end gate. In the present instance the end gate is shown as made in two sections 5 and 6 respectively, the sections being detachably locked together by means of a spring clip 7 secured to the upper section 6 as shown at 8, and provided with an inturned lip or flange 9 which engages a suitable recess 10 in the lower section 5. It is to be understood of course, that the number of sections in which the end gate may be made, may be varied as desired, or may be made all in one piece. To receive the end gate there is secured to each of the side boards a vertically extending channel member 11. The base member 12 of each of these channels is provided with a web-like extension 13, 14, by which it may be more readily secured to the adjacent side board. The inner vertically extending flange 15 of the respective channel members 11, in effect serves as a track rail for the anti-friction rollers of the end gates, hereinafter described.

Describing now the coöperating interlocking members carried by the end gate, each 35 section is provided at its vertical edge with a channel member 20, which is secured to the outer face of the end gate by means of a web or flange extension 21 as shown more clearly in Figs. 3 and 4. Within each of 40 these channel members 20 is rotatably journaled a plurality of anti-friction rollers 22, so arranged that when the end gate is in position the wheels will normally ride on the track rail 15 of the coöperating channel 45 member 11. To prevent the end gate from outward displacement, on the inside of each end gate section is fixedly secured a confining flange 23, the outer end of which is 50 preferably provided with an off set extension 24 which overlaps the adjacent side of the corresponding channel 11. The arrangement of the parts just described is such that the end gate is not only locked against lateral displacement but acts as a tie to prevent 55 spreading of the side boards under pressure of a load. At the same time by reason of the anti-friction rollers the end gate may be easily withdrawn without binding for the purpose of unloading. To prevent vertical displacement of the end gate, as well 60 as to avoid rattling I provide a bottom sec-

tion 5 with a spring latch bar 25, the ends of which are provided with offset portions 26 terminating in right angle extensions 27. The ends 27 of the latch bar pass through 5 suitable apertures in the sides of the channel members 20 and are adapted to have locking engagement with the similar apertures in the adjacent channel member 11. The off set portions 26 in effect serve as hand holds 10 to which the ends 27 of the latch bar may be readily withdrawn from engagement with the channel member 11 in order to remove the end gate. Preferably the intermediate portions of the latch bar are confined in 15 suitable eyes 28 as shown more clearly in Figs. 1 and 2.

The manner in which the end gate is removed or inserted in place is obvious from the foregoing description and need not be 20 described further in detail. It is understood of course, that in inserting the end gate in place or removing it, the latches should be withdrawn from engagement with the channel members of the side boards. 25 Preferably the channel members and locking flanges 23 are made of sheet metal so as to avoid binding by warping. It should be noted not only that the interlocking channel members may be easily and cheaply 30 constructed but that the end gate and side boards are effectively locked without the aid of any tie rods and without the necessity of using any wrench, or other tools as is necessary in constructions now in general use. I 35 am aware that heretofore various forms of end gates have been patented, but none of them, as far as I know, have embodied the simplicity and effectiveness found in the present construction. It should also be 40 noted that when the end gate is in position it is flush with the adjacent edge of the side boards and that the parts so interlock as to

form in effect a grain tight seal at the rear end of the wagon.

The invention is not limited to the details 45 of construction shown except as set forth in the appended claims.

I claim as my invention:

1. The combination with a wagon body the side boards of which are provided at the 50 rear end with vertical channel members, the open sides of which face rearwardly, of an end gate provided at each end with a vertical channel member the open sides of which face the ends of said gate, a flange extension secured to the inner face of said gate at each end, and anti-friction rollers journaled 55 between the sides of channel members of the gate and adapted to travel in contact with the inner or free flanges of the channel members of the side boards.

2. The combination with a wagon body the side boards of which are provided at the 60 rear end with vertical channel members, the open sides of which face rearwardly, of an end gate provided at each end with a vertical channel member the open sides of which face the ends of said gate, a flange extension secured to the inner face of said gate at 65 each end, anti-friction rollers journaled between the sides of channel members of the gate and adapted to travel in contact with the inner or free flanges of the channel members of the side boards, registering 70 openings in the channel members of the side boards and gate ends, and a spring latch bar provided at its ends with angular extensions 75 adapted to fit the openings of said channel members.

JOSEPH H. KOEBEL.
